P. M. HASSSLER

CONNECTION FOR TRACK HANGERS

Filed April 11, 1927

UNITED STATES PATENT OFFICE.

PAUL M. HASSSLER, OF FAIRFIELD, IOWA, ASSIGNOR TO THE LOUDEN MACHINERY COMPANY, OF FAIRFIELD, IOWA, A CORPORATION OF IOWA.

CONNECTION FOR TRACK HANGERS.

Application filed April 11, 1927. Serial No. 182,682.

My invention relates to connections for hangers adapted to sustain overhead trackways upon which carrying devices are to run, and it especially relates to means to connect these hangers to overhead supporting structures used in the frames of buildings, such as I beams etc., and it consists of means whereby said trackways may be supported and laterally as well as vertically adjusted on said supporting structures. Also, of other features in the construction of connections for track hangers which will be hereinafter set forth, and will be definitely defined in the claims.

In the accompanying drawings, forming a part of this specification, Fig. 1 is a vertically disposed transverse section of a structure embodying my invention, a portion of the structure being broken away, as will be hereinafter explained. Fig. 2 is the same of an upper portion of Fig. 1, some of the parts being shown in a different position. Fig. 3 is a vertically disposed section on line 3—3 of Fig. 1 looking in the direction of the arrow at the upper end of the line. Figs. 4 and 5 are perspectives of certain parts which will be hereafter described.

Referring to the drawings, A A represents the lower flanges of an I beam, such as are used in the construction of the metallic frame work of buildings, and B is a small portion of the central web of the I beam, the main portion of the web and the upper flanges of the beam being broken away. C is a track-rail of ordinary construction which is connected to the I beam as follows.

A pair of clamping members D D held together mainly by a bolt E, are arranged to have their lower ends catch over and hold the bead on the upper portion of the track rail C in the usual manner. These clamping members are fitted with a link F having its lower ends open and fitted with heads which are adapted to enter and hold in recesses in the inner faces of the clamping members D D and to be adjusted to lengthen and shorten the hanger in the usual manner, the link F and the clamping members D D thus arranged, being generally known in the art as "track hangers".

My invention relates to the method of connecting the links F of said track hangers to the I beams or other supporting member, forming a portion of the framework of the

building in which the track-rail C is installed. In so doing, I use a member G, which may be called a double ended bolt, having long threaded ends and a depressed or curved portion g in its center. This bolt is passed through the upper portion of the link F, and clamping members H having central apertures, are slipped on to the ends of the bolt.

These clamping members H are fitted on their upper ends with inwardly extending lugs h h which are adapted to catch over the upper edges of the flanges of the I beam when used, and to be held in contact therewith by the nuts or burrs J, screwed onto the ends of the bolt G. By this means the link F and the clamping member D holding the bead of the track-rail C between them, will be securely connected to the flanges A A of the I beam. To make the hold on the flanges of the I beam more secure, the portions h' h' of the clamp H, below the bolt G, are lengthened inwardly to form braces which will counteract the pressure of the inwardly extended lugs h on the upper edges of the flanges A.

In order to hold the track hanger, composed of the link F and clamping member D, more rigidly in position, I use a central member, preferably composed of two parts K K fastened together by means of a rivet L, or in place of the rivet a bolt may be used. The inner sides of the lower portions of the parts K are hollowed out to admit the link F, and also to permit the passage of the bolt G through the link. The members are preferably made tapering on the outer sides, as shown by Figs. 1 and 4, with their lower ends closely fitting the link F, and with inwardly projecting portions K coming in contact with an upper portion of the link.

The members K are preferably held in contact with the lower surface of the flanges A of the I beam by means of the bolt G coming in contact with shoulders K' K' on said members. Also, to hold the members K more securely in place, the upper ends are broadened and the central part is preferably hollowed out, as shown in the drawings. If preferred, the members K may be made integral with its center cored out to secure the results specified, and when so made the rivet L will not be needed.

When installing the track-rail, it is fre-

quently necessary to adjust it laterally as well as vertically. The vertical adjustment has already been largely provided for by the type of track hangers composed of the link 5 F and clamping members D. To adjust the track-rail laterally all that is necessary with my invention is to loosen the nut or burr on one end of the bolt G, and to tighten the nut or burr on the other end, as shown by 10 Fig. 2, which shows a lateral adjustment of the track-way C and its attachments in one direction. To adjust it in the opposite direction, simply reverse the operation. The longer the bolt G and its threaded ends, the 15 greater the adjustment which may be made.

The members K assist in holding the track-rail more securely in its lateral adjustment by preventing the swinging of the track hanger, and it also assists in preventing the 20 tipping of the track-rail, as it is sometimes liable to do when carrying a heavy load over a curved portion. My invention may also be used with other forms of frame work where metallic I beams are not used by dispensing 25 with the clamps H, and using other form of connections known to the art, which are adapted to be connected to the other forms of framework, such as wooden beams and the like, and which will provide for lateral ad- 30 justments.

My invention may also be used to make a slight vertical adjustment of the position of the track-rail by tightening or loosening the nuts or burrs J, the tightening tending to 35 draw the curved portion of the bolt up closer to the I beam. This adjustment will of course be limited by the heads of the members K, but for some uses the members K may be dispensed with and then the vertical 40 adjustment may be increased. With any modifications which may be made my invention is extremely simple and effective in operation.

What I claim as new and desire to secure 45 by Letters Patent is:

1. In connections for hangers to support overhead track-ways, the combination with 50 an overhead supporting member of a substantially horizontally disposed double ended bolt member having long threaded ends with nuts or burrs thereon, means to attach the bolt member to the overhead supporting member, whereby said bolt member may be laterally adjusted thereon, and a track sup- 55 porting hanger connected to a central portion of the bolt member.

2. In connections for hangers to support 60 overhead track-ways, the combination with an overhead supporting member of a sub- 65 stantially horizontally disposed double ended bolt member having a downwardly curved portion in its center, long threaded ends with nuts or burrs thereon, means to attach the bolt member to the overhead sup- 70 porting member, whereby said bolt member may be

laterally adjusted thereon and a track sup- 75 porting hanger connected to said downwardly curved portion of the bolt.

3. In a device of the character described, the combination with an overhead metallic I beam, of a substantially horizontally disposed double ended bolt member having long threaded ends with nuts or burrs thereon, clamping members on the bolt adapted to catch over the edges of the lower flanges of the I beam and hold the bolt member in engagement therewith, and also to permit the lateral adjustment of the bolt thereon, and a track supporting hanger connected to a central portion of the bolt member. 80

4. In a device of the character described, the combination with an overhead metallic I beam, of a substantially horizontally disposed double ended bolt member having a downwardly curved portion in its center and long threaded ends with nuts or burrs thereon, clamping members on the bolt adapted to catch over the edges of the lower flanges of the I beam and hold the bolt member in engagement therewith and also to permit the lateral adjustment of the bolt thereon, and a track supporting hanger connected to the 85 downwardly curved portion of the bolt. 90

5. In connections for hangers to support overhead trackways, the combination with an overhead supporting member of a substantially horizontally disposed double ended bolt member having a downwardly curved portion in its center and long threaded ends with nuts or burrs thereon, means to attach the bolt member to the overhead supporting member, whereby said bolt member may be laterally adjusted thereon, a link of a track hanger hung in the depressed curved portion 100 of the bolt member and a central depending member having its upper end held against the lower side of the overhead supporting member, and its lower portion forked to straddle the central portion of the bolt member, and also the link of the track hanger, 105 whereby the latter will be held rigidly in an upright position. 110

6. In connections for hangers to support overhead trackways, the combination with an overhead supporting member of a sub- 115 stantially horizontally disposed double ended bolt member having a downwardly curved portion in its center and long threaded ends with nuts or burrs thereon, means to attach the bolt member to the overhead supporting member, whereby said bolt member may be laterally adjusted thereon, a link of a track hanger hung in the depressed curved portion 120 of the bolt member, and a central depending member composed of two parts joined together and having its upper end held against the lower side of the overhead supporting member, and its lower portion forked to straddle the central portion of the bolt member, and also the link of the track hanger, 125 130

whereby the latter will be held rigidly in an upright position.

7. In connections for hangers to support overhead trackways, the combination with 5 an overhead supporting member, of a substantially horizontally disposed double ended bolt member having a downwardly curved portion in its center and long threaded ends with nuts or burrs thereon, means to attach 10 the bolt member to the overhead supporting member, whereby said bolt member may be laterally adjusted thereon, a link of a track hanger hung in the depressed curved portion of the bolt member, and a central depending 15 member having its upper end held against the lower side of the overhead supporting member, and its lower portion forked to straddle the central portion of the bolt member, and also the link of the track hanger, 20 whereby the latter will be held rigidly in an upright position, said central depending member having shoulders to rest against adjacent portions of the bolt member.

8. In connections for hangers to support overhead trackways, the combination with 25 an overhead supporting member, of a substantially horizontally disposed double ended bolt member having a downwardly curved portion in its center and long threaded ends with nuts or burrs thereon, means to attach 30 the bolt member to the overhead supporting member, whereby said bolt member may be laterally adjusted thereon, a link of a track hanger hung in the depressed curved portion of the bolt member and a central depending member having its upper end held against the lower side of the overhead supporting member, and its lower portion forked to straddle the central portion of the bolt member, and also the link of the track 35 hanger, the lower end of said central depending member having its outside tapered, and being provided with inwardly extending portions to bear against to hold the track hanger link rigidly in upright position.

PAUL M. HASSSLER.
